UNITED STATES PATENT OFFICE.

ARTHUR SCHILLER, OF CHICAGO, ILLINOIS.

DESIGN FOR A MATCH-BOX HOLDER.

Application filed May 24, 1922. Serial No. 2,407. Term of patent 3½ years.

To all whom it may concern:

Be it known that I ARTHUR SCHILLER, citizen of the United States, residing at Chicago, in the county of Cook and State of Illinois, have invented a new, original, and ornamental Design for a Match-Box Holder, as shown in the accompanying drawing and described in the following specification.

Fig. 1 is a side elevation of the improved design for match box holder, Fig. 2 is a plan view of the same, and Fig. 3 is an end elevation of the same.

I claim:

The ornamental design for a match box holder, as shown.

ARTHUR SCHILLER.

Witnesses:

FRANCES SCHLACHT,
ELKA KOHN.
